UNITED STATES PATENT OFFICE.

ERWIN L. SUTTER, OF WASECA, MINNESOTA.

WASHBOARD.

1,302,991.

Specification of Letters Patent.

Patented May 6, 1919.

Application filed September 30, 1916. Serial No. 123,102.

To all whom it may concern:

Be it known that I, ERWIN L. SUTTER, a citizen of the United States, residing at Waseca, in the county of Waseca and State 5 of Minnesota, have invented new and useful Improvements in Washboards, of which the following is a specification.

This invention relates to improvements in wash boards and has particular application 10 to a self-soaping wash board.

In carrying out the present invention, it is my purpose to provide a self-soaping wash board whereby the soap may be automatically applied to the articles being rubbed 15 upon the board in the downward movement, and automatically brought into position to be engaged by the clothes in the upward movement.

It is also my purpose to provide a self-soaping wash board which will embrace the desired features of simplicity, efficiency and durability, and which will operate efficiently, and effectively for its intended purpose, and which may be manufactured and marketed 25 at small cost.

With the above and other objects in view, the invention consists in the construction, combination and arrangement of parts hereinafter set forth in and falling within the 30 scope of the claims.

In the accompanying drawing;

Figure 1 is a front elevation of a wash board constructed in accordance with the present invention.

Fig. 2 is a similar view showing the cover of the soap pocket in open position.

Fig. 3 is a sectional view on the line 3—3 of Fig. 1.

Fig. 4 is a sectional view on the line 4—4 of Fig. 1.

Referring now to the drawing in detail, 1 designates a wash board which, in accordance with the present invention, is formed with a pocket 2 at the upper end of the rubbing 45 section of the board and mounted within the pocket and suitably secured therein is a receptacle 3 having the front end open. Journaled in the end walls of the receptacle 3 at the lower side of such 50 receptacle is a shaft 4 and mounted upon the shaft 4 between the end walls of the receptacle is a feeding roller 5 preferably formed with longitudinally extending ribs spaced apart about the roller and having the outer 55 edges roughened. Arranged adjacent to the

rear wall of the casing is a follower plate 6 and interposed between the rear wall of the receptacle or casing and the follower plate are springs 7 acting to force the follower plate outwardly toward the feeding roller. 60 Fixed upon one end of the shaft 4 is a ratchet wheel 8, while secured to the adjacent end wall of the receptacle is a spring dog 9 engaging the ratchet wheel 8 to hold the shaft and the roller against rotation in 65 one direction and permit the same to rotate in the other direction. Hinged to the wash board above the pocket is one edge of a cover plate 10 designed to close the pocket and the forward portion of the receptacle 70 and having the lower edge formed with a slot 11 through which the roller 5 works, as clearly illustrated in Fig. 1 of the drawing.

In practice, the soap, which may be either 75 in cake or bar form, is placed between the follower plate and the roller and the springs act to hold the soap against the ribs on the roller. The cover plate 10 is then closed and in the use of the board, when the articles being washed are moved upwardly the 80 roller 5 is rotated so that the ribs in engagement with the soap may rub over such soap and move through the slot 11. On the downward movement of the articles being washed, the roller is held against movement 85 under the action of the pawl and ratchet wheel, and the articles rubbing over the roller remove the soap from the exposed ribs, thereby soaping such articles.

While I have herein shown and described 90 the preferred form of my invention by way of illustration, I wish it to be understood that I do not limit or confine myself to the precise details of construction herein described and delineated, as modification and 95 variation may be made within the scope of the claims and without departing from the spirit of the invention.

I claim:

1. In combination with a wash board having the usual soap pocket above the rubbing surface thereof, of a casing having an open face secured in said pocket and spaced from the side walls thereof, a shaft extending through bearing openings in the sides of the 100 casing, a roller in the casing secured to said shaft, a follower plate in the casing, spring means between said plate and the top wall of the casing for forcing the plate toward the roller, means in the pocket, to one side 105 110

of the casing for restraining the shaft against turning in one direction, a hinged plate let in depressions in the sides of the pocket for covering the open face of the casing, and said plate having a notch receiving therethrough a portion of the periphery of the roller, when the plate is in closed position.

2. An attachment for washboards, comprising a casing designed to be seated in and secured to the soap pocket of a washboard, said casing having an open outer face, a

roller journaled in the casing, a spring influenced follower plate above the roller, means between the washboard and the roller, arranged exteriorly of the casing for holding the roller against movement in one direction, a cover plate for the casing, and said cover plate having its lower edge notched to receive therethrough a portion of the periphery of the roller.

In testimony whereof I affix my signature.

ERWIN L. SUTTER.
